UNITED STATES PATENT OFFICE.

HENRY S. PARKER, OF FULTON, ILLINOIS.

BARREL-TRUCK.

SPECIFICATION forming part of Letters Patent No. 615,040, dated November 29, 1898.

Application filed August 17, 1898. Serial No. 688,819. (No model.)

To all whom it may concern:

Be it known that I, HENRY S. PARKER, a citizen of the United States, residing at Fulton, county of Whiteside, State of Illinois, have 5 invented certain new and useful Improvements in Barrel-Trucks; and I do declare the following to be a full, clear, and exact description of the invention, such as will enable others skilled in the art to which it appertains to 10 make and use the same, reference being had to the accompanying drawings, and to the letters of reference marked thereon, which form a part of this specification.

My invention has reference to improvements 15 in barrel-trucks, and is especially adapted to be used in lifting and conveying barrels of apples, flour, sugar, molasses, salt, &c., weighing from fifty to three hundred and fifty pounds with equal ease and by the employment 20 of but one operator. The mechanism by which I accomplish this consists of the mutual action of two members suitably carried on a wheeled frame, by means of which the barrel is lifted, loaded, wheeled to its desired 25 location, and set down in place without being touched by the hand of the operator.

In groceries, stores, and warehouses where many barrels are moved daily my truck is found to be of great assistance in the saving 30 of time and strength.

In lifting apple-barrels great care must be taken to avoid disturbing the apples, and my truck provides a way in which they can be moved without any jar or shock.

35 I accomplish the above objects by the mechanism illustrated in the accompanying drawings, in which—

Figure 1 is a perspective of a detail of my invention. Fig. 2 is a perspective of my invention, showing the barrel loaded on the truck in position for wheeling.

Similar letters refer to similar parts in each view.

40 A and B are levers intermediately pivoted by the bolt C to the attaching-plate G of the axle of the carrying-frame. On the forward portion of the levers A and B are formed the circular arms D, provided at their upper forward extremities with the small spurs or 45 points E. The rear of the levers A and B are

adapted to be coincidently grasped in the hands of the operator and forced toward each other as in the case of ordinary tongs.

The levers A and B are supported and carried upon a wheeled frame H, provided with 55 an attaching-plate G, to which said levers are pivoted, as aforesaid, by the bolt C, the plate G being firmly braced to the axle H' of the frame H by means of a suitable bracket L. The end portions of the axle H' are bent forward at right angles to the main portion and carry at their extremities the wheels K.

It is my purpose to manufacture the rear or hand portions of the levers A and B of piping or some similar material in order to reduce 60 their weight and the remainder of my truck of steel, the arms D being suitably welded or riveted to said rear portions of the levers A and B.

In the operation of my invention the operator 65 grasps the rear portions of the levers A and B as he would a pair of tongs, and by raising said ends lowers the clasping-arms D until the points E are in position to grasp the barrel to be moved about the center of its 70 lower hoop. The ends A and B are then forced toward each other, which action also forces the points E into the hoop aforesaid. As the 75 said ends of A and B are gently lowered the barrel, using the points E as pivotal points, 80 swings rearwardly into the arms D, as shown in Fig. 2, being firmly held by them. It can then be pushed to any desired location and the barrel swung back to its perpendicular position on the floor by the raising of the levers 85 A and B. The barrel can then be released from the points E by the forcing apart of the rear ends of A and B.

My truck can be manufactured in different sizes. A large size can be made by means of 90 which, operated by two persons, the large-sized molasses-barrels can be easily moved.

What I claim as my invention, and desire 95 to secure by Letters Patent of the United States, is—

1. In a barrel-truck, the combination of the levers A and B, the arms D, points E formed at the extremities thereof respectively, plate G on which said levers are fulcrumed, U-shaped axle H', on which said plate G is 100

formed, and carrying wheels K thereon, substantially as shown and for the purpose specified.

2. In a barrel-truck, angular axle H', plate 5 G on which are fulcrumed levers A and B, and carrying wheels K, on the ends of axle H', substantially as shown and for the purpose specified.

3. In a barrel-truck the combination of the 10 axle H' provided with plate G and wheels K,

and the levers A and B provided with arms D having points E, intermediately pivoted to each other and to the plate G, substantially as shown and for the purpose described.

In testimony whereof I affix my signature 15 in the presence of two witnesses.

HENRY S. PARKER.
